SCREEN ASSEMBLY FOR GRINDING MILLS

Filed Sept. 4, 1931

2 Sheets-Sheet 2

Fig. 2.

Technical drawing of a vertical structure, likely a component of a machine or apparatus. The drawing is labeled 'Fig. 3.' at the top left. The structure is composed of several vertical and horizontal bars, with a central vertical bar featuring a grid of circular holes. Various components are labeled with numbers:

- Top horizontal bar: 52, m, 9, 52
- Left side: 48, 51, 46, 49, 53, 37, 43, 60, 35, 33, 31, 58, 59, 45, 60, 47
- Central vertical bar: 29, 50, 27, 50, 28, 51, 48, 49, 36, 42, 34, 32, 30, 59, 26, 545, 57, 56, 53, 60, 54, 53, 47
- Bottom horizontal bar: 5, 4, 3, m, 52

SCREEN ASSEMBLY FOR GRINDING MILLS

Otto N. Gredell, Kansas City, Mo., assignor to
Standard Steel Works, North Kansas City,
Mo., a corporation of Missouri

Application September 4, 1931. Serial No. 561,173

18 Claims. (Cl. 83—11)

This invention relates to grinding mills and more particularly to those of that character employing screens through which reduced material is discharged from the grinding chamber, and 5 has for its principal object to provide an improved mounting for the screens whereby they are securely anchored in position to co-operate with the grinding elements of the mills.

It is also an object of the invention to provide 10 for ready removal and application of the screens when it is desired to substitute screens of different mesh in order to grind all of the various kinds of commodities encountered in custom grinding.

15 In accomplishing these and other objects of the invention I have provided improved details of structure, the preferred form of which is illustrated in the accompanying drawings wherein:

Fig. 1 is a vertical elevational view partly in 20 section of a grinder equipped with a screen embodying my invention.

Fig. 2 is a fragmentary detail perspective view 25 of a portion of the grinder illustrating the clamping members for securing the screen.

Fig. 3 is a detail sectional view on the line 3—3 of Fig. 2 particularly illustrating mounting of 30 the screen in the grinder casing.

Fig. 4 is a sectional view through the casing 35 and sealing elements at the upper end of the screen on the line 4—4 of Fig. 2, and

Fig. 5 is a similar view through the sealing elements at the opposite end of the screen.

Referring more in detail to the drawings:

1 designates a grinder casing including vertical side plates 2 and 3 spaced apart by a substantially circular band 4 to form a cylindrical rotor chamber 5. The ends 6 and 7 of the band terminate short of each other to provide a radial discharge outlet 8 opening to an exhaust chamber

40 9. The exhaust chamber 9 is defined by upward extending portions of the side plates and by spaced plates 10 and 11 having the width of the band 4. The plate 10 extends vertically between the side plates at a point spaced from a vertical tangent to the circular band and its lower end is bent inwardly at an angle to terminate in a footing flange 12 which seats on the projecting flange of an angle member 13. The angle member is fixed across the width of the band at a point spaced below its terminal edge

45 to form a screen engaging ledge 14 for a screen later described.

The other plate 11 has its upper end co-operating 50 with the upper end of the plate 10 to form a neck 15 to secure an exhaust conduit 16 and

its lower end inclines downwardly to rest on the band 4 at a point spaced from its end 6. The end of the band thus forms a ledge 17 complementary to the ledge 14 previously described.

The band 4 including the plates 10 and 11 are 60 clamped in position between the side plates by bolts 18, certain of the bolts extending through triangle shaped loops 19 welded to said members as shown in Fig. 1.

Rotatably mounted within the rotor chamber 65 is a shaft 20 carrying a rotor disk 21 having a plurality of pivotally mounted hammers 22 and radial cutter blades 23 that co-operate with a fixed cutter blade 24 mounted adjacent a feed inlet opening 25. The specific construction of the 70 rotor, however, forms no part of the present invention.

The outer edges of the hammers move through a path in close proximity with the inner surface 75 of the band 4 to co-operate therewith in reducing material drawn into the chamber through the inlet opening 25 formed in one of the side plates 2 or 3. The hammers also serve to create a fan blast for discharging reduced material through the discharge outlet and through the exhaust 80 conduit 16.

In order that the material may be retained within the grinding zone until it has become reduced to the proper size the discharge outlet is 85 closed by a screen 26 having a mesh or apertures 27 proportionate to the desired degree of fineness to which the material is to be ground.

It is important that the screen be secured 90 tightly within the casing since the impacts caused by the centrifugally revolving mass will cause the screen to bulge outwardly and become displaced. It is also important that the screens be mounted for quick change when changing from one type of material to another so that the machine is adaptable to custom grinding as now 95 described.

The side plates 2 and 3 are provided with arcuate slots 28 and 29 respectively extending between the lower ends of the plates 10 and 11 so that an arcuate shaped screen may be inserted therethrough to permit its ends to rest against the ledges 14 and 17 and substantially form a continuation of the band 4 bridging its gap.

Fixed to the side plates 2 and 3 exteriorly 105 thereof are arcuate shaped angle members 30 and 31 having laterally projecting flanges 32 and 33 positioned with their upper faces aligning with the inner arcuate edges of the slots 28 and 29 to form ledges 34 and 35 to support projecting side edges 36 and 37 of the screen 26 as shown in Fig. 3.

The lower ends of the angle members extend beyond the lower ends of the slots while their upper ends may align with the slots to accommodate sealing blocks 38 and 39 at the upper and lower ends respectively.

The upper sealing blocks are preferably formed of rectangular blocks of rubber substantially the width of the ledges and are slidably mounted in socket members 40 welded to the side plates adjacent the upper ends of the angle members, the blocks being seated on springs 41 which tend to lift them from the sockets to seal against the upper ends of clamping strips 42 and 43.

The lower blocks 39 are slightly wider than the width of the clamping strips and are secured to the ledges by rivets or the like, so that the ends of the clamping strips may abut thereagainst for sealing the space formed between the clamping strips and the flanges of the angle members.

The clamping strips are to extend over the outer surface of the projecting sides of the screen and are preferably formed of a Z-bar bent into an arcuate shape similar to the curvature of the screen whereby the flanges 44 thereof lie against the outer faces of the side plates and form closures for the arcuate slots 28 and 29 and the flanges 45 overlap the side edges of the screen.

The flanges 45 also overlap the projecting flanges 32 and 33 of the angle members 30 and 31, while the intermediate horizontal portion 46 lies flat on the screen.

In order to seal the side edges of the screen to co-operate with the sealing blocks in preventing leakage of air through the slots, the inner faces of the flanges 45 are provided with rubber or like strips 47 which are preferably riveted to the flanges 45 of the clamping strips and the lower ends thereof abut against the blocks 3 while the upper ends overlap the sealing blocks 38 to effect seals therewith.

It is thus apparent that the horizontal portions 46 of the clamping strips lie flat on the projecting sides 36 and 37 of the screen while the screen lies flat against the ledges 34 and 35 and the screen is retained thereby at a fixed distance from the ends of the hammer, but the clamping strips may be shifted laterally toward the sides of the casing to compress the sealing strips 47 against the edges of the flanges 32 and 33, effecting tight seals and preventing escape of air.

In order to retain the clamping strips in position, I provide clamping lugs 48 located at intervals along the length thereof. The clamping lugs are preferably provided with body portions 49 having flat seats 50 to engage the horizontal portions of the clamping strips and having tongues 51 which project upwardly therefrom to engage in loops 52. The body portions of the lugs are also provided with downwardly inclined arms 53 having notches 54 to admit bolts 55 carried by anchoring members 56.

The loops 52 are spaced radially from the slots 28 and 29 and are preferably welded to the side plates 2 and 3.

The anchoring members are clips having ends 57 secured to the angle members at points in line with the loops and having slotted ends 58 inclined downwardly substantially parallel with the arms 52 of the lugs.

The bolts 55, having heads 59 to engage under the clips, are extended through the slotted ends 58 and through the notches 54 in the lugs and are provided with wing nuts 60 whereby the arms of the lugs may be drawn towards the casing, which tilting of the lugs causes the body

portions thereof to engage in the angle formed by the portions 44 and 46 of the clamping strips to draw the strips down tightly against the screen and at the same time against the sides of the casing to close the slots. This clamping movement of the clamping strips also draws the rubber strips tightly against the edges of the arcuate ledge members for effecting a seal to exclude air from blowing through the slots.

Assuming that a screen has been assembled in the grinder and it is desired to change the screen for one of different mesh, the wing nuts 60 are loosened to allow the bolts 55 to drop from the notches 54 in the lugs 48. The lugs 48 are then

80

85

90

95

100

free to be removed after which the clamping strips 42 and 43 are lifted from the screen. The screen may then be slid sidewise through either of the slots 28 or 29 and withdrawn. A screen having the proper size apertures may then be

slid edgewise through one of the slots until both of its edges project equally from the sides of the casing and lie on the ledges 34 and 35. The clamping strips 42 and 43 are then applied over

the projecting portions of the screen with the

flanges 44 closing the unused portions of the slots

and the flanges 45 engaging and overlapping the

flange of the angle members 30 and 31.

The lugs 48 are applied with the tongues 51 engaging in the loops 52 and the body portions 49 seated within the angles of the clamping strips formed between the portions 44 and 46 thereof, after which the bolts 55 are swung into the notches 54. The wing nuts 60 are then tightened against the arms 53 to draw the clamping strips into

105

110

clamping position. The screen is thus held rigid because both side edges thereof are clamped throughout their entire length and its ends are drawn against the ledges 14 and 17. With the screen thus anchored

there is very little possibility of its buckling or moving out of position due to the violent impacts produced in the grinding operation. It is also

impossible for the reduced material to escape around the edges of the screen. The reduced

material is, therefore, all forced through the apertures of the screen to obtain a uniform reduction

of the comminuted material.

It is also apparent that due to the seals effected by the sealing members it is impossible for the air generated by the rotor to escape through the screen slots.

115

What I claim and desire to secure by Letters Patent is:

1. In a grinding mill of the character described, a rotor casing including side walls having slotted openings therethrough, ledge members fixed to said side walls adjacent said openings, a screen member in the casing having side edges resting directly on said ledge members, clamping strips covering the slotted openings, resilient strips carried by the clamping strips and engaging the edges of the screen to effect a seal, and clamp members for securing the clamping strips in clamping contact with the screen and the resilient strips against the screen and ledge members.

120

2. In a grinding mill of the character described, a rotor casing including side walls having slotted openings, ledge members fixed to said side walls adjacent said openings, a screen member in the casing having side edges resting directly on said

125

ledge members, clamping strips engaging the opposite face of the screen, sealing means associated with the clamping strips and engaging side edges of the screen, and means for anchoring said

130

135

140

145

150

- clamping strips in engaging position with the screen and with said sealing means.
3. In a grinding mill of the character described, a rotor casing including side walls having aligning arcuate slots, arcuate ledge members fixed to the casing adjacent said slots, a screen member in the casing having side edges projecting through said slots and resting on the ledge members, arcuate clamping strips associated with the ledge members to retain the edges of the screen therebetween, loops fixed to the casing at one side of the slots, bolt anchoring means aligned with the loops at the opposite sides of the slots, lugs engaging the loops and the bearing on the clamping strips, and bolts carried by said anchoring means for securing the lugs.
4. In a grinding mill of the character described, a rotor casing including side walls having aligning arcuate slots, arcuate ledge members on the casing adjacent said slots, a screen member in the casing having side edges projecting through said slots and resting on the ledge members, an arcuate clamping strip associated with the ledge members to retain the edges of the screen therebetween, loops fixed to the casing at one side of the slots, bolt anchoring means aligned with the loops at the opposite sides of the slots, lugs bearing on the clamping strips, tongues on the lugs engaging the loops, arms projecting from the lugs laterally of the clamping strips and bolts extending through the arms, and the anchoring means to secure the lugs in clamping engagement with the clamping strips.
5. In a grinding mill of the character described, a rotor casing including side walls having aligning arcuate slots, arcuate ledge members fixed to the casing adjacent said slots, a screen member in the casing having side edges projecting through said slots and resting on the ledge members, an arcuate clamping strip associated with the ledge members to retain the edges of the screen therebetween, flexible sealing strips associated with the clamping strips to effect a seal with the edges of the ledge members, and yielding sealing members at the ends of said ledge members to effect a seal with the ends of the clamping strips.
6. In a grinding mill, a rotor casing including side walls having arcuate slots, a band member cooperating with the side walls to form a rotor chamber and having its ends terminating adjacent the ends of said slots to form a discharge outlet, an arcuate screen member insertable through said slots and having its ends resting on the ends of said band member to cover said discharge outlet, and means fixed to the side walls of the housing and closing said slots including means for clamping the ends of the screen to the ends of the band member.
7. In a grinding mill, a casing including side walls having aligning arcuate slots, a circular band member cooperating with said walls to form a grinding chamber and having its ends terminating adjacent the ends of said slots to form a discharge outlet, an arcuate screen member covering the discharge outlet and having its ends engaging the ends of said band member and its sides projecting through said slots, ledge members supporting the projecting edges of said screen, arcuate clamping members associated with the ledge members to retain the edges of the screen therebetween and the ends of the screen in engagement with the ends of the band member, and fastening devices for securing said clamping members in position.
8. In a grinding mill, a casing including side walls having aligning arcuate slots, a circular band member cooperating with said walls to form a grinding chamber and having its ends terminating adjacent the ends of said slot to 80 form a discharge outlet, an arcuate screen member covering the discharge outlet and having its ends engaging the ends of said band member and its sides projecting through said slots, ledge members supporting the projecting edges of said screen, arcuate clamping members associated with the ledge members to retain the edges of the screen therebetween, loops fixed to the side walls at one side of said slots, bolt-anchoring means aligned with the loops at the opposite sides of the slots, lug members engaging the loops and engaging the clamping members, and bolts engaging said anchoring means and the lug members for retaining said clamping strips.
9. In a grinding mill, a casing including side walls having aligning arcuate slots, a circular band member cooperating with said walls to form a grinding chamber and having its ends terminating adjacent the ends of said slot to 85 form a discharge outlet, an arcuate screen member covering the discharge outlet and having its ends engaging the ends of said band member and its sides projecting through said slots, ledge members supporting the projecting edges of said screen, arcuate clamping members associated with the ledge members to retain the edges of the screen therebetween, loops fixed to the side walls at one side of said slots, bolt-anchoring means aligned with the loops at the opposite sides of the slots, lug members engaging the loops and engaging the clamping members, and bolts 90 engaging said anchoring means and the lug members for retaining said clamping strips.
10. In a grinding mill, a casing including side walls having aligning arcuate slots, a circular band member cooperating with said walls to form a grinding chamber and having its ends terminating adjacent the ends of said slot to 95 form a discharge outlet, an arcuate screen member covering the discharge outlet and having its ends engaging the ends of said band member and its sides projecting through said slots, ledge members supporting the projecting edges of said screen, arcuate clamping members associated with the ledge members to retain the edges of the screen therebetween, lug members engaging the loops and engaging the clamping members, and means on the side walls at opposite sides of said slots for anchoring said lug members.
11. In a grinding mill of the character described, a casing, ledge members fixed to the casing, clamp members associated with the ledge members, a screen having its edges engaged between the ledge members and the clamp members, and resilient means engaging the edges of the screen and the ledge members for sealing the screen with said members.
12. In a grinding mill, a rotor casing including spaced side walls and having an arcuate-shaped opening in one of said side walls, arcuately arranged screen supports on the side walls, an arcuate-shaped screen insertable through said opening to engage said supports, an arcuate-shaped member covering said opening and directly engaging the face of the screen directly above said support adjacent the opening, a compressible strip positioned between the arcuate-shaped member and a side edge of the screen to prevent leakage of material from the grinding mill, and means engageable with the casing for clamping the arcuate member against the screen and the screen against said support in position over said opening.
13. In a grinding mill, a rotor casing including spaced side walls and having an arcuate-shaped opening in one of said side walls, arcuately arranged screen supports on the side walls, an arcuate-shaped screen insertable through said opening to engage said supports, an arcuate-shaped member covering said opening and engaging the screen on the side opposite said supports, a compressible strip positioned between the arcuate-shaped member and an edge of the screen to prevent leakage of material from the grinding mill, clamping members engageable with the casing and having a portion engaged with the arcuate-shaped member, and clamping bolts extending through said clamping members tighten the arcuate member against the adjacent screen.

support and the compressible strip against the edge of the screen.

13. In a grinding mill, a casing including a side wall having an arcuate slot, arcuately arranged screen supports on the casing in alignment with said slot, an arcuate screen member insertable through said slot, an arcuate clamping member associated with one of said supports to retain the edge of the screen therebetween, loops fixed to said side wall at one side of the slot, bolt-anchoring means aligned with the loops at opposite sides of the slot, lug members engaging the clamping member and having arms engaging the loops and arms extending outwardly from the clamping member, and bolts engaging said anchoring means and the extending arms of the lug members for securing the clamping strip against the screen and the screen against the support to prevent radial movement of the screen.

14. In a grinding mill of the character described, a rotor casing including a side wall having an arcuate slot, arcuately arranged ledge members fixed to the casing adjacent said slot, a screen member in the casing having its edges resting on said ledge members and projecting through said slot, an arcuate clamping strip associated with the ledge member adjacent said slot to clamp the edge of the screen firmly to the ledge member, a flexible sealing strip associated with the clamping strip to effect a seal with the edge of said ledge member, and sealing members at the ends of said ledge member to effect a seal with the clamping strip.

15. In a grinding mill of the character described, a casing, ledge members fixed to the casing, clamp members associated with the ledge members, a screen having its edges resting directly upon the ledge members and having its opposite faces directly engaged by the clamp members, and a yielding sealing material engaging the side edges of the screen and the ledge members to effect a seal with the ledge members.

16. A grinding mill of the character described, a rotor casing including side walls having arcuate slots, ledge members fixed to the side walls in alignment with edges of the slots, an arcuate screen member extending through the slots and having side edges resting on the ledge

members, arcuate clamping strips having flange portions directly engaging the screen above the ledge members and having laterally extending flanges overlapping side edges of the ledge members, sealing strips between the lateral flanges and the ledge members, and means for clamping the clamping strips to the ledge members to retain the edges of the screen thereagainst and the sealing strips in sealing relation with the ledge members and side edges of the screen.

17. In a grinding mill of the character described, a rotor casing including side walls having arcuate slots, ledge members fixed to the side walls in alignment with edges of the slots, an arcuate screen member extending through the slots and having side edges resting on the ledge members, arcuate clamping strips having horizontal portions engaging the screen above the ledge members, lateral flanges extending from opposite edges of the horizontal portions for closing said slots and overlapping side edges of the ledge members, sealing strips between the ledge members and the overlapping lateral flanges, and means for clamping the clamping strips to the ledge members to retain edges of the screen thereagainst and the sealing strip in sealing contact with the ledge members and the edges of the screen.

18. In a grinding mill of the character described, a rotor casing including a side wall having an arcuate slot, ledge members fixed to the casing in alignment with an arcuate edge of the slot, an arcuate screen member extending through said slot and having side edges resting on the ledge members, an arcuate clamping strip having a horizontal portion directly engaging the screen member extending through said slot and having oppositely directed lateral flanges on opposite sides of the horizontal portion for closing said slot and overlapping the edge of said ledge member, a sealing strip between the edge of the ledge member and the overlapping flange to sealingly engage the edge of the screen, and means for clamping the clamping strip to the ledge member to retain the screen thereagainst and the sealing strip in sealing contact with the ledge member and the edge of the screen.
